UNITED STATES PATENT OFFICE.

WILLIAM J. GOLDSWORTHY, OF SAN FRANCISCO, CALIFORNIA.

GOLF PRACTICING AND TRAINING DEVICE AND METHOD.

Application filed April 23, 1925. Serial No. 25,349.

The invention relates generally to devices and method whereby through use of the same, at home or away from the golf course, a person's actual game on the course may be 5 improved.

The invention is directed in particular towards a practicing method and device whereby the player in practice may self-tutor himself in and acquire some very important 10 actions to be observed during the swing of the club when hitting a ball in the actual game. One essential action is known in golf as the "keeping the head down" or "keeping the eye on the ball", synonymous 15 terms for the same thing, another as "pivot-ing on the hips" and another as the "follow-through", all contributing towards desired straightness of direction in the flight of the ball as well as desired distance.

20 A brief explanation of what is meant in golf by the above terms will lead to a better understanding of the particular objects of the proposed method and device.

In the game of golf, when the player 25 poses to hit a ball from its "lie" with a club swung by his hands, he will take his "stance" (placing of the feet) in an estimated proper relation to the ball and reach out the club-head to a point near the ball, 30 generally touching the club-head to the ground immediately behind the ball (known in golf as "soling the club"). From such "soling" of the club he may determine, if his stance is the proper distance from the ball and if not shift it and at the same time settle himself into that position in relation to the ball from which he feels he can most 35 forcefully hit the ball. All golf authorities and experts agree that a stiff erect position of the body and head should be abandoned and, accompanying the actions of the player to settle himself into a forceful hitting position, that the head and body of the player should be gradually, but not abruptly, inclined 40 forward and downward, accomplishing a movement similar in nature to a salutation or bow, from which salutation or bending forward and downward of the body and head has sprung the term "addressing 45 the ball" now used to cover a number of the actions of the player preliminary to and anticipating the actual withdrawal of the club and club-head away from its "soled" position (known in golf as "taking the club 50 back") to that distance back of the ball from where it will be returned with force against

the ball in the actual hitting of the ball. Authorities agree, and during the development of this invention it has been found, that in the bending forward and downward 60 of the head in properly "addressing the ball", the head should and does proceed progressively in a forward and downward direction and, if the proper "address" has been continued, at the time that the player 65 begins in "taking the club back" his actual effort to hit the ball, that the head will have assumed its farthest forward and downward position (its lowest, closest approach to 70 towards the ball). Whatever bowed position 75 the head may have thus reached (and this may vary as to each individual player), authorities and experience agree that, for the best results, no lifting of the head from the position should occur until the blow with 80 the club has been made, the ball hit by the club-head and the club-head has passed "through" and beyond the spot from where the ball has been driven. To lift the head is to invite an indifferent and unsatisfactory 85 flight of the ball even if hit. The foregoing explains the golfing terms "keeping the head down" and "keeping the eye on the ball".

Again up to the time of the explained 85 "taking the club back" the eyes of the player have, obviously, been fixed on the ball and, when striving to exert himself to the utmost in hitting the ball, the player will in 90 "taking the club back" turn his body to the right (if a right handed player) to a greater or lesser distance and during such a movement and during the succeeding left turn of the body, in the blow, the ball should not be lost to the sight of the player until after being hit by the club. To illustrate, it is possible for a person, wishing to view objects on his right or on his left, to turn his head to the right or left without a movement of the torso, the neck furnishing a flexible connection between the two permitting this movement. Now in making a correct stroke in golf the above action is reversed and the head should be held practically immovable, in the inclined downward and forward position already described as "keeping the head down", and the torso, with the shoulder and arms, is turned, the head serving as the upper immovable bearing, with the 100 flexible turnable neck connecting it to the torso, and the ground serving as the lower immovable bearing, with the feet, legs and 105 110

hips furnishing, in increasing progressive degrees, the necessary flexible turnable connections between it and the torso. Thus the torso, leaning obliquely, executes, in the blow, a rocking or rolling movement. This rocking or rolling motion of the torso, with the accompanying effort of the arms, wrists and hands, begun at the "taking of the club back" and continued until the ball has been 10 hit, the ball being always in view, until hit, and the head down, as explained above, is assigned by all competent judges as being an important feature of a golf stroke, if not the most important. The foregoing explains 15 the golfing term "pivoting on the hips."

Again all authorities agree that, after the ball is hit, the club-head should not leave the straight line of the flight of the ball, where the ball has been sent straight away in its 20 correct direction, but should follow after the ball in that straight line for some distance from where the ball has been hit (known in golf as the "follow-through"), the tendency of the player being to let the head come up 25 just as the ball is hit, a tendency which is cautioned against by all authorities on the game. The foregoing explains the golfing term "follow-through."

If the foregoing statements are fair and 30 correct, and it is so believed, then it is to be admitted that the practically immovable inclined position of the head assumed for and during the stroke should be maintained during a certain immediate coherent portion of 35 the stroke while the force exerted for the stroke is being launched sustained and carried through by other members of the body. This will require muscular action by a player which will be to him entirely new 40 and demanding coordinate and synchronized action of muscles not before attempted and that already acquired, and what to the player would seem natural, muscular actions for putting force into the blow must be 45 broken down and, as it were, thrown off.

To attain this correct action in a golf stroke, it has been the general method heretofore, for the player to do his practicing and try out his work under the eye and tutorage of a professional teacher of the game. But teachers of golf agree that the correct 50 execution of the above particularized actions is of the hardest for the practicing player to comprehend and attain and of the hardest 55 for the tutor to intelligibly impart to the player. The action in hitting a ball is so rapid that, as the head is free to move, a movement of the head may escape the eye of the most competent instructor, his attention 60 being claimed at many points at the same time. Set directions adapted for one player may be totally unadapted for others. Golfing lessons do not always bring to the student the satisfactory results anticipated, due 65 to the player's inability to translate the

given instructions into action and also to interfering individual muscular and temperamental peculiarities. The above method, boldly stated, is one man swinging and hitting at a ball with a golf club with a second man standing by telling the first how to do it with the first trying to do what the second tells him. This method is governed by so many personal limitations of both the actors that often no satisfactory results 70 whatever are produced.

The applicant has thought it well to abandon the above method and devote his efforts towards developing a method whereby the player could self-tutor himself in 80 the requirements of the perfect stroke, as set forth at length above, and by which the player would, in practicing, at once be brought to a knowledge of what correlated muscular actions should occur to make the 85 correct stroke and under mechanical guidance self acquire and drill himself in those actions and impose them on himself. He now proposes, in practicing golf strokes 90 away from the course, with a club in hand 95 and a ball or substitute in place to be hit, the novel method of when and as the player's head progressively and freely assumes the farthest forward and downward position attained thereby, for and in executing the 100 stroke,—then forcibly restraining the head in that position against a retrograde upward and backward movement, then continuing the forcible restraint into and during the execution of the stroke until the ball has been 105 hit and then after that eliminating the forcible restraint by the action of the club in the stroke and thus freeing the head for unrestrained movement during the remainder of the stroke.

Thus, while the product is not claimed as new, the offered method of production and the offered device for production are, the same being, in effect, the feeding into a machine, operated by the player himself, of 110 raw material in the shape of a player with loose unsynchronized and uncoordinated muscular action and turning the material into a finished desirable article in the shape of a player with fixed synchronized and coordinated muscular action.

The distinction between the function of the machine and a product of the machine being made plain in the above example justifies the device and the method claims which 115 will follow.

The applicant proposes and shows a device by which his above proposed method may be carried out, the particulars of which follow.

In the accompanying drawing—

Fig. 1, is an isometric view of the device.

Fig. 2, is a detail of a part of the device on a larger scale.

Attention is called to the applicant's co- 120

pending application Serial No. 639,291, as the present invention includes some of the features thereof.

In carrying out my invention in the manner shown, a base 1, which is intended to set upon the surface played upon and to one side of the line of play, is provided and supports the uprights 2. A pintle 3 is preferably rigidly connected to the uprights 2. A plate 4 is provided with one end bent around the pintle 3 so that it will freely revolve thereon, between the uprights 2, in the manner of a hinge or latch. The free swinging end of the plate 4 has a preferably inturned arcuate shape in order to serve as a guide for and retain a member intended to actuate the plate 4. Although the same ends could be served, where the supports 2 extend beyond the free end of plate 4, by the supports 2 and have the free end of the plate 4 otherwise shaped.

Serrations 5, to act as engaging means to act in and intensify the hold of the plate 4 on a member intended to contact therewith, are provided on the free end of the plate 4, or the free end of the plate 4 is fashioned into sharp engaging claws or serrations for that purpose. A cap 7, as usually worn by golfers, is shown as if on the head of the player. A hook 8 engages in the cap 7 and is disengageable therefrom at the will of the player. An elongated member 9, here shown in broken relation between the cap 7 and the plate 4, to one end of which the hook 8 is secured, is provided of a length sufficient to extend from the cap of the player, when making a strike, to contact with and pass over the plate 4 with a depending end below the plate 4 and between the uprights 2. The elongated member 9 may be formed from any suitable material, preferably light in weight, as wire, wooden or bamboo strip, woven fabric tape, spun cord, etc. The materials mentioned having been tried, but for the purpose of this description the spun cord form will be adhered to.

Where a cord is used for the elongated member 9, it has been found advisable to provide a weight 10 to serve as a tensing means to secure the desired friction of the elongated member 9 against the free end of the plate 4, a lead sinker, as used in angling, can be utilized as the weight 10 for and maintaining a continual pull on the head of the player. Upon the cord 9 a series of irregularities 11 are provided which may be fashioned in ways adapted to the material from which the elongated member 9 is fashioned, i. e., bends in a wire, teeth on a wooden strip, buttons on a strap, or where a cord is used and means are provided to tense the cord, the irregularities 11 may consist of knots made in and from the cord 9. The irregularities 11 also may be fashioned from material heavy enough to tense the cord 9 and eliminate the weight 10. For this purpose small split shot, as used in weighting a fishing line, securely fastened to the cord 9 have been found adaptable. In the present drawing and description the split shot 70 irregularities 11 and the lead weight 10 are both shown connected to the elongated cord member 9, such associated use also being found satisfactory as well as their disassociated use. It is found advisable that the 75 irregularities 11 should occur on the elongated cord 9 at regular distanced spacing from each other. Slots 12 are provided in the uprights 2 extending through each of the supports 2 at points opposite each other. 80 A laterally extending arm 13 is provided to slide and move freely in the slots 12. The slots 12 are fashioned to restrict a vertical movement of the arm 13 while allowing the movement or shifting of the arm 13 in a 85 horizontal plane into a variety of positions. The ends of the arm 13 are extended beyond the support 2 and, through the capable adjustment of the same in the slots 12 or through a bend in the same, one of the ends 90 extends out and over the fore line of the swing of the club-head when the player executes his practice stroke. Depending from the arm 13 and reaching the surface played upon is a blow receiving part 14. The blow 95 receiving part 14 may be integral with the arm 13, merely being a down turned portion thereof, or preferably be depended from the arm 13 and capable of being detached therefrom under the force of the blow of the 100 club-head, which is intended in its flight to contact with the blow receiving part 14 and move it in a direction with its line of travel. A rupturable connection is made between the 105 arm 13 and the blow receiving part 14 by 110 an eye 15 being formed at the end of the arm 13. Through the eye 15 one end of the blow receiving part 14 is passed and then more or less loose turns of the end of the blow receiving part 14 are made around the 115 arm 13. The blow receiving part 14 being formed from some material sufficiently pliable for this use; spun cord or twine, leather or rubber being found adaptable.

An upright bar 16 extending from the arm 13 upward to and opposite the plate 4, is provided on the arm 13. The upright bar 16 is provided with an integral foot 18 adapted to grip the arm 13 and be slidable thereon. A removable holding bolt 19 is provided, adapted to pass through a bore in the slidable foot 18 and through any selected one of a series of bores 20 provided on and through the arm 13, to hold the upright bar 16 and slidable foot 18 stationary 120 at desired points on the arm 13. At the upper end of the upright bar 16 two prongs or bills are provided extending laterally therefrom, an upper 17 and a lower 17, shown in the drawing as integral with the 125

upright bar 16. The upper prong 17 is fashioned to pass closely over the plate 4 and the lower prong 17' to pass closely under the plate 4 for the limited distance necessary to secure a clamping action on the plate 4 so that when the upright bar 16 is held immovable the prongs 17 and 17' will hold the plate 4 immovable, the prongs 17 and 17' being fashioned to be slid into and out of a clamping relation with the plate 4. The term detent could be applied to the arrangement as a whole of the prongs 17 and 17' rigidly secured to the upright bar 16 which in turn, for the time, is in immovable connection with the arm 13 with the arm 13 incapable of an upward and downward movement in the slots 12 but capable of an entering and retiring movement in the slots 12. For, so conditioned, when the prongs 17 and 17' are predisposed, as intended, to clamp the plate 4, the plate 4 will be locked from turning on the pintle 3 and, when the arm 13 is retired from the slots 12 sufficiently to withdraw the prongs 17 and 17' from contact with the plate 4, the plate 4 will be unlocked and be free to turn on the pintle 3. In this manner the definition of a detent—as that which locks or unlocks a movement—will be satisfied. The outline of the ball 18' is shown on the surface played upon in its position, in relation to the device, from where it is intended that the player will hit it away by a blow or stroke with the club-swung by his hands. The arrows *x* show the approximate path of the club-head of the club before the ball 18' is hit and the arrows *x'* show the same path after the ball 18' has been hit.

20 shows an horizontally revolving bar freely pivoted on a pin 21 extending through a bore in the horizontally revolving bar 20 and rigidly set in the base 1. A register 24 as ordinarily used to transmute revolutions of a shaft into expressions on a dial is secured to the base 1 and the shaft 23, operating the mechanism of the register, is shown projecting therefrom with the fingers 22 rigidly secured thereon in contact with and intended to be actuated by the revolving bar 20. No mechanism of the register 24 is shown as it is intended that any revolving shaft operated register may be used adapted for the purpose of registering the kinetic force of the blow of the club swung by the player hitting the ball 18' and the bar 20 and operating portions of the device. 25 is a pin setting in a bore or bores in the arm 13 to prevent the arm from being entirely withdrawn from the slots 12.

The parts of device being provided and assembled into operable relation as described, the player, in using the same in practicing and training himself in matters

concerning his play to which it appertains, will set the base 1 of the device on the surface practiced upon and see that the base 1 is firmly secured to such surface. He will then place a practice ball 18' or substitute therefor on the surface played upon at the end of the pivoted bar 20 protruding from the base 1. He will then select, in the straight line of the probable fore flight of the ball after it has been hit, a point to where the club should be carried before leaving that line and then move the arm 13 so as to have the depending blow receiving part 14, suspending from the eye 15, of the arm 13, to hang perpendicularly through that point, shifting the arm 13 in the slots 12 so that the depending blow receiving part 14 will hang in air at the proper point. The end of the blow receiving part 14 connecting with the arm 13 being already passed through the eye 15 and wrapped on the arm 13, and being careful not to disturb this set position of the arm 13, he will slide the sliding foot 18 on the arm 13 until the integral upright 16 moves the prongs 17 and 17' into a locking position with the plate 4, the plate 4 being at the same time turned on the pintle 3 to present itself in the position to be locked by the prongs 17 and 17'. The removable bolt 19 will then be inserted in and through the bore in 18 and a bore in 13 where it will hold, through the means of the foot 18, upright 16 and prongs 17 and 17', the plate 4 locked against a movement 100 on the pintle 3. The cord 9, with the associated parts shown, is then connected to the cap 7 by the hook 8 and the cap 7 set as tightly and as rigidly on the head of the player as comfort will allow. The player with club in one hand, then faces the device on the side where the ball lies and for the moment stands close to, if not actually over, the ball 18'. He then grasps the cord 9 near the middle thereof with the other hand and lifts the weight 10 over the plate 4 and allows the weight 10 to come to a rest just under the arcuate shaped end of the plate 4 with the portion of the cord 9 immediately above the weight 10 115 in and bent over the arcuate shaped end of the plate 4 to be held in frictional contact therein.

The player then backs away from the device towards the location where his stance 120 will be taken for the hitting of the ball 18' allowing, at the same time in retiring, the cord 9 to play through his hands, maintaining at the same time sufficient pull on the cord 9 to have the weight 10 to maintain its first placed position immediately under the arcuate end of the plate 4. When the player reaches his stance position he assumes an erect upright stand with the head well up and then releases his hand hold on 120

the cord 9. This will cause the weight 10 to at once drop and taking up the slack of the cord 9 will establish a continuous pull on the head of the player, through the hook 8 and the cap 7. Both hands of the player will now be used to grasp the club. From his erect position the player will now begin "addressing the ball" allowing his head, at the same time, to incline forward and downward until he has the feel that he is all "set" to make the stroke. During the forward and downward movement of the head, the weight 10 will again drop and pull the cord 9 and the irregularities 11 over the arcuate end of the plate 4. The irregularities 11 on the cord 9 being adapted to disengagingly slide over the arcuate end of the plate 4 and the serrations 5 in the forward and downward frictional movement 20 of the cord 9 and to immediately engage in and with the arcuate end of the plate 4 if a retrograde upward and backward movement should be attempted and immediately stop such retrograde movement. The serrations 25 5 on the plate 4 being also adapted to permit the disengaging forward and downward frictional movement of the cord 9 and to insert in the cord 9 and irregularities 11 and immediately prevent any retrograde upward 30 and backward movement of the cord 9. The "address" being completed and the head of the player, having assumed, as it will, its farthest forward and downward position, (nearest related position to the ball), will obviously be prevented, by the means connected 35 therewith and operating as described, from being lifted backwardly and upwardly and the head of the player will be then actually locked in its farthest forward and downward position while the prongs 17 and 17' clamp the plate 4 and will continue to be so locked against any backward and upward movement until the prongs 17 and 17' are retired from the plate 4. With his head so locked the player now executes his stroke and after the ball 18' is hit by the club-head of the club of the player the club-head will hit the depending blow receiving part 14, predisposed in the line of swing of the club-head, as explained, and tend to violently carry the same with it causing the blow receiving part 14 to pull on the arm 13. From and through this sudden pull, the arm 13 will be retired from the slots 12 and the prongs 17 and 17' will be retired from locking relation with the plate 4, thereby freeing plate 4 to be actuated by and turned on the pintle 3 in any upward and backward movement of the head of the player through 50 the cap 7 hook 8 cord 9 and narrated associated means acting on the plate 4 and then and thereby unlocking the head of the player and restoring the free movement of his head to the player. The pin 25 will, in 55 the meantime, have been moved to and

against the upright 2 stopping the further movement of the arm 13 and thus causing the connecting end of the blow receiving part 14 to unroll and separate from the arm 13 and all of the part 14 to be carried away 70 by the club-head. It is obvious that the angle with which the plate 4 meets the cord 9 can be varied, by setting the pin 3 higher or lower in the supports 2; and again a series of slots 12 may be made in the supports 75 2 above and below each other and the arm 13 extended as desired, over the surface played upon, at a higher or lower position than shown, making the upright bar 16 adjustable upwardly or downwardly on the 80 arm 13 and to rigidly connect therewith at its different high or low positions to still carry the prongs 17 and 17' into their proper gripping position for the plate 4; all being equivalents of the principle already 85 shown and explained. At the time the ball 18' is hit by the club-head, the end of the pivoted revolving bar 20 will also be hit and be revolved on the pin 21 and will contact in its revolutions 90 with the fingers 22, in succession, causing them, in turn, to revolve and thus give to the shaft 23 the necessary revolving motion required to operate the register 24. It has been found that, when the blow receiving part 14 is formed from absorbent material like spun cord or twine, wetting that portion with water where the club-head will hit into it will cause a greater cling of the blow receiving part 14 to the club-head and increase its tendency to be carried away by 95 the club-head. Or the lower depending end of the blow receiving part 14 may be doubled back on itself for a short distance thereby adding weight to its end which will 100 increase its tendency to cling to and be carried away by the club-head. If the blow receiving part 14 is provided integral with the arm 13 of comparatively non-pliable material, it will be necessary, in order to avoid 105 an undue shock, to allow for the arm 13 to entirely retire from the slots 12. In this case the pin 25 is omitted from its place on the arm 13 and an anchoring cord of comprehensive length may be fastened by one 110 end to the arm 13 or parts in union therewith, with the opposite end fastened to some stationary part of the device. Such anchoring cord would stop the arm 13 and united parts at a distance from the device and cause 115 it to fall from the club-head. It has been found desirable to eliminate as much as possible any noisy operation of the device, so the rupturable turned connection between the blow receiving part 14 and the arm 13, 120 as described, can be so made as to resist just sufficient force of the blow to move the arm 13 and then to leave the arm 13. 125

It has been found desirable at times to practice with the blow receiving part 14 130

serving as a force signal or goal only without the head restraining and releasing features. In this case there will be used the base 1, the uprights 2, the slots 12, the arm 13 and the blow receiving part 14, with or without the register 24 and means operating it, all formed and assembled as above explained. The eye 15 being also provided in the arm 13. Then, the ball 18', or substitute, being in place to be hit and the base 1 and uprights 2 being set to one side of the line of swing of the club-head, the arm 13 will be adjusted in the slots 12 to rest at some desired point over the fore line of the travel of the club-head after the ball has been hit, with the eye 15 above that line. The blow receiving part 14 will then be depended from the arm 13 in the proper line of the fore travel of the club-head and separably connected with it by having one end pass through the eye 15 and loosely turned around the arm 13 so as to be easily separated therefrom and carried away when hit by the club-head. The arm 13, if desired, may be wedged in the slots 12 to render it immovable. The player then hits the ball 18' and exerts his effort in the stroke to carry the club-head "through" and out to and hit the blow receiving part 14. By shifting the arm 13 or base 1 so that the depending blow receiving part 14 hangs at greater or less distances away from the ball in the fore line of play, the player is required to make greater or less efforts to carry the club-head through. In each blow the club-head as it hits into the blow receiving part 14 will noiselessly separate it from the arm 13 thus informing the player that the club-head has been properly "carried through", or if the blow receiving part 14 is missed by the club-head and remains hanging to the arm 13 the player will be thus informed that the club-head has not been properly "carried through". The noiseless removal of the blow receiving part 14 from the arm 13, as described, has been found quite acceptable and advantageous adding much to the composure and confidence of the player in making the blow. The register 24, if used at this time, is operated at the time the ball 18' is hit by the club by and through the means already described as hit by the club and operating the same.

During the development of the device, when using the same in the limited quarters of a house room, the applicant has found that the use of a ball may be dispensed with and the stroke made at and over a selected point on the surface played upon where the ball, if used, would lie. Strokes made in such a manner, as already described where ball is used, bring to the player the proper play of muscular action desired and save time by relieving him of the need of retrieving and replacing the ball after each stroke and also avoids noise and the contact of the

flying ball with the walls or furniture of the room and the possible damage thereto.

It has already been proposed to apply restraint to different members of the body during golf practice. Such proposals are directed towards applying the restraint while the player is at rest and before any of the preliminaries of the actual effort to hit the ball have taken place and to a removal of the restraint after the stroke has been entirely completed and the player is again at rest. The present proposition differentiates itself from the above in being directed towards producing in the player harmonious correlated muscular actions by automatically applying compulsory restraint to the head of the player only after all the preliminaries to the stroke have been made and the actual effort of the player to hit the ball is occurring and then automatically freeing the head from such compulsory restraint during the stroke at some desired point in the stroke and before all of the stroke has been completed. The term stroke as used in this description is intended to include the fore travel of the club after the ball has been hit and until the club has been brought to rest. Also the term automatically is used in the sense that where an impulse is directed towards one result the said impulse is made to effect another and additional result, without direct manual aid.

Having thus illustrated my invention and described the same in detail, what I claim as new and desire to secure by Letters Patent is:

1. In a golf practicing and training device the combination with an elongated means in detachable connection with the head-wear of the player and transmitting movements of the head of the player to and actuating a supported operable member of the device freely moving on the support, of a detent means, adapted to lock the said supported operable member against movement and unlock the same for movement, and means in connection with the detent means adapted to receive and convey a force, exerted thereon and moving the same, to the detent means for operating the detent means.

2. In a golf practicing and training device the combination with an elongated means in detachable connection with the head-wear of the player and transmitting movements of the head of the player to and actuating a supported operable member of the device freely moving on the support, of a detent means, adapted to lock the said supported operable member against movement and unlock the same for movement, and an extension carried by the detent means, adapted to receive and convey a force exerted thereon to the detent means for operating the same.

3. In a golf practicing and training device the combination with an elongated means in detachable connection with the

head-wear of the player and transmitting movements of the head of the player to and actuating a supported operable member of the device freely moving on the support, of a detent means, adapted to lock the said supported operable member against movement and unlock the same for movement, provided with an extension adapted to be carried into the fore line of travel of and be hit and moved by a club swung by the hands of the player and thereby actuate the said detent means.

4. In a golf practicing and training device the combination with an elongated means in detachable connection with the head-wear of the player and transmitting movements of the head of the player to and actuating a supported operable member of the device freely moving on the support, of a detent means, adapted to lock the said supported operable means against movement and unlock the same for movement, and a blow receiving means connected with the said detent means and extended to the fore line of travel of the club swung by the player, adapted to be hit and moved by the club and thereby actuate the detent means.

5. In a golf practicing and training device the combination with an elongated means in detachable connection with the head-wear of the player and transmitting movements of the head of the player to and actuating a supported operable member of the device freely moving on the support, of a detent means, adapted to lock the said supported operable member against movement and unlock the same for movement, provided with an extension adapted to be placed over the fore line of travel of a club swung by the player and a blow receiving means depended from the said extension in the fore line of travel of the club, adapted to be hit and moved by the club and actuate the said detent means.

45 6. In a golf practicing and training device the combination with an elongated means in detachable connection with the head-wear of the player and transmitting movements of the head of the player to and actuating a supported operable member of the device freely moving on the support, of a detent means, adapted to lock the said supported operable member against movement and unlock the same for movement, provided with an extension adapted to be placed over the fore line of travel of a club swung by the player, a blow receiving means depended in the fore line of travel of and hit and moved by the club and a rupturable connection between the said blow receiving means and the said extension, adapted to be ruptured, under the force applied by the club to the blow receiving means, after the detent is actuated.

65 7. In a golf practicing and training de-

vice the combination with an elongated means in detachable connection with the head-wear of the player and transmitting movements of the player to and actuating a supported operable member of the device 70 freely moving on the support, of a detent means, adapted to lock the said supported operable member against movement and unlock the same for movement, a blow receiving means supported in the fore line of 75 travel of and adapted to be hit and moved by the club swung by the player and operative connections between the blow receiving means and the detent means, adapted to convey the club actuated movement of 80 the blow receiving means to the detent means to operate the detent means.

8. In a golf practicing and training device the combination with an elongated means in detachable connection with the head-wear of the player and transmitting movements of the head of the player to and actuating a supported operable member of the device freely moving on the support, of a detent means, adapted to lock the said supported operable member against a movement and unlock the same for movement, carried by the support and capable of adjustment thereon through means provided on the support and a blow receiving member 85 in operative connection with the detent, for operating the detent.

9. In a golf practicing and training device the combination with an elongated means in detachable connection with the head-wear of the player and transmitting movements of the head of the player to and actuating a supported operable member of the device freely moving on the support, of a detent means, adapted to lock the said supported operable member against movement and unlock the same for movement, provided with an extension adapted to be placed over the fore line of travel of a club swung by the player, a blow receiving 100 means depended from the said extension in the fore line of travel of the club, adapted to be hit and moved by the club and actuate the said detent means, a pivoted revolving member, adapted to be hit and actuated by 105 the club during the blow, and a register means operated by and recording the revolutions of the pivoted revolving member.

10. In a golf practicing and training device in combination, a base, adapted to be set to one side of the fore line of travel of the club-head, an upright carried by the base, an arm carried by the upright laterally extended therefrom, adapted to be positioned over the fore line of travel of the club-head and a blow receiving means carried by the arm, loosely depended from the arm, adapted to be positioned in the fore line of travel of the club-head.

11. In a golf practicing and training de-

vice in combination, a base, adapted to be set to one side of the fore line of travel of the club-head, an upright carried by the base, an arm carried by the upright laterally extended therefrom, adapted to be positioned over the fore line of travel of the club-head, and a depending blow receiving means loosely carried on the arm, adapted to be positioned on the arm in the fore line of travel of the club-head and to be separated from the arm under the force of a blow from the club-head.

12. In a golf practicing and training device in combination, a base, adapted to be set to one side of the fore line of travel of the club-head, an upright carried by the base, an arm carried by the upright laterally extended therefrom, adapted to be positioned over the fore line of travel of the club-head, a depending blow receiving means carried by the arm, adapted to be positioned in the fore line of travel of the club-head and a rupturable connection joining the depending blow receiving means to the arm, adapted to be ruptured under the force of a blow from the club-head.

13. In a golf practicing and training device in combination, a base, adapted to be set to one side of the fore line of travel of the club-head, an upright carried by the base, an arm carried by the upright laterally extended therefrom adapted to be positioned over the fore line of travel of the club-head, a depending blow receiving means loosely carried on the arm, adapted to be positioned on the arm in the fore line of travel of the club-head and to be separated from the arm under the force of a blow from the club-head, a pivoted revolving member, adapted to be hit and actuated by the club-head during the blow, and a register means operated by and recording the revolutions of the pivoted revolving member.

14. In golf practicing and training the method of producing co-ordinated muscular

action in a player, during a practice stroke with a club swung by the player, by allowing the head of the player to progressively acquire the farthest forward and downward position assumed thereby for and in making the stroke, then subjecting the head to a compulsory restraint against a retrograde upward and backward movement, then continuing the said restraint into and for a portion of the stroke and then discontinuing the said restraint and restoring the free movement of the head for the remainder of the stroke.

15. In golf practicing and training the method of producing co-ordinate muscular action in a player, during a practice stroke with a club swung by the player, by allowing the head of the player to progressively acquire the farthest forward and downward position assumed thereby for and in making the stroke, then subjecting the head to a mechanical restraint against a retrograde upward and backward movement, then continuing the said mechanical restraint for a predetermined portion of the stroke and then discontinuing the said mechanical restraint and restoring the free movement of the head for the remainder of the stroke.

16. In a golf practicing and training device the combination with an elongated means in detachable connection with the head-wear of the player and transmitting movements of the head of the player to and actuating a supported operable member freely moving on the support, of a detent, adapted to predeterminedly lock the head actuated movable member against movement, an elongated blow receiver, positioned to be hit and moved by the club of the player, and operative connections between the blow receiver and the detent, adapted to convey a movement of the blow receiver to the detent for actuating the detent.

WILLIAM J. GOLDSWORTHY.
